UNITED STATES PATENT OFFICE.

MASON ALBERT HAWKINS, OF BALTIMORE, MARYLAND.

MUSIC-CABINET.

1,135,281.

Specification of Letters Patent. Patented Apr. 13, 1915.

Application filed May 14, 1914. Serial No. 338,494.

To all whom it may concern:

Be it known that I, MASON A. HAWKINS, a citizen of the United States, and a resident of Baltimore, State of Maryland, have invented a new and Improved Music-Cabinet, of which the following is a full, clear, and exact description.

My invention relates particularly to a holder for the music rolls of player pianos, 10 and the like.

The objects of the invention are to provide for accommodating the maximum number of music rolls in a given space; to embody the novel elements in a form constituting 15 units of a sectional cabinet; to provide trays for the music rolls each adapted to hold a series of rolls and accommodate rolls of different diameters; to provide for holding the rolls of a series in parallel orderly relation on the trays; and to provide a sliding music roll holder, and a door at the front of the holder together with novel connecting means for actuating the door by the movements of the sliding holder.

25 Other purposes and advantages of the invention will appear from the specific description hereinafter given.

Reference is had to the accompanying drawings forming part of this specification, 30 in which similar characters indicate corresponding parts in all the views.

Figure 1 is a perspective view of a series of units embodying my invention showing the same supported on top of a player instrument. Fig. 2 is a perspective view of a sectional cabinet embodying my invention. Fig. 3 is a longitudinal vertical section of 35 one of the units embodying the invention. Fig. 4 is a fragmentary cross-sectional view 40 on line 4—4 in Fig. 3, and Fig. 5 is a plan view of one of the holder trays.

The invention is embodied in rectangular units designated generally by the numeral 10, these being preferably oblong and 45 adapted to be disposed in longitudinal series on top of a player instrument indicated by the letter A, or to form elements in a sectional cabinet as shown in Fig. 2, in which a base 11 of known form is shown, and a 50 top 12. Each unit 10 is generally of box-like form and preferably has horizontal portions 13 and vertical portions 14 dividing the structure into separate compartments. Each compartment is provided with 55 a door 15 hinged at its upper edge as at 16, and within the compartment is a sliding

holder in the form of a tray 17. To properly hold the music rolls on the tray transverse rest members 18 are provided having V-shaped notches 18^a, the notches of the 60 respective parallel rests 18 on each tray being in longitudinal alinement, so that a roll will have support on two rests. In practice I provide a series of notches in each rest 18, three being shown in the present instance, so that the plurality of the 65 rolls will be held in parallel relation. As indicated by dotted line Fig. 4, the V-shaped notches accommodate rolls of different 70 diameter. At the front and rear end of each tray 17 broad bottom members 19, 20, are employed, and the back 17^a of the tray forms a stop limiting the rearward movement of the rolls and serving to properly aline the latter. It will be observed from 75 Fig. 3 that the front 17^b of each tray is depressed below the top edges of the rests 18 so as to permit free longitudinal movement 80 of the rolls to and from the tray. The music rolls are indicated by the letter B. To secure the tray in position a resilient 85 catch device 21 is provided shown jointly in the form of a plate spring secured at its inner end to the underside of the tray and having a catch 22 adapted to spring into a 90 notch 24 in the bottom 10^a of the structure 10. The outer free end 23 of the catch projects beyond the front of the structure 10 and constitutes a handle for releasing the 95 catch and withdrawing the tray to afford 90 convenient access to the rolls.

I provide a novel means whereby the longitudinal movements of the trays will open and close the doors 15. The said means consists of operating rods 25 arranged longitudinally of the trays, each rod having an articulated connection as at 26 with an arm 27 on the door. The tray is equipped with motion-imparting means in the form of trips 28, 29, hereinafter referred to as trips, to 100 actuate the rod 25 and to form guides for the latter, so that the rod may have longitudinal and vertical play in the said trips in response to the movements of the door and tray. Preferably each trip 28, 29, consists 105 of an upwardly extending member having a longitudinal slot 30, the lower ends of the trips being secured in any suitable manner to a side of the tray as by producing pointed ends 28^a, 29^a on said trips and driving the 110 same vertically into the tray. For engagement of the trips 28, 29 with the door oper-

2
ating rod 25, said rod is provided with adjustable members 31, 32 slidable on the rod to different positions and securable in adjusted position by set screws 33, 34. The 5 front member 31 is forward of the front trips 28, while the rear member 32 is rearward of the rear trip 29. The relative positions of the trips and the members 31, 32 to be engaged thereby are such that the tray 10 will have a limited movement relatively to the rod 25, it being sufficient that the tray actuate the rod 25 during the period only of the movement of the tray.

To gain access to the music rolls in a particular compartment, the catch 22 is released by means of the handle 23 which extends outwardly through an opening 15° in the door 15. The lower portion of the door lies in front of the tray, so that as the latter is drawn outward by means of the handle 23 the tray will contact with the door, partially swinging the latter, and the door will ride up on inclines 17° on the sides of the tray, thereby enabling the tray to clear the 25 door in the initial movement of the tray, after which the front trip 28 will engage the forward projection 31 on the trip rod and actuate said rod to further lift the door. The reverse action takes place in moving the 30 tray inwardly, and during the latter part of the movement the rear trip 29 will engage the adjacent member 32 and move the rod 25 rearwardly to close the door, the action of the parts being timed to bring the door 35 to the closed position in front of the tray as the catch 22 engages its notch 24.

Having thus described my invention, what I claim as new and desire to secure by Letters Patent is—

40 1. A structure of the character described having a compartment, a holder slidable in the compartment, a swinging door for closing the compartment, a door opening and closing member in the compartment, a connection between said member and the door, and trip means on the holder to actuate said member in opposite directions by the movements of the holder.

2. A structure of the character described 50 having a compartment, a holder slidable longitudinally in the compartment, a door for closing the compartment in front of the holder, a door opening and closing member connected with the door, said holder having a limited sliding movement relatively to the 55 said opening and closing member, and trips on the holder to actuate the said member after a limited movement of the holder in either direction.

60 3. A structure of the character described

having a compartment, a slidable holder therein, a door for closing the compartment, a door opening and closing device ranging longitudinally of the holder and connected with the door, trip means carried by the 65 holder and embracing the said door opening and closing device to guide the same, and spaced elements on the said door opening and closing device engageable by the said trip means in the movements of the 70 holder.

4. A structure of the character described having a compartment, a slidable holder therein, a door for closing the compartment, a door opening and closing rod ranging longitudinally of the compartment adjacent to the holder, spaced trip members carried by the holder at a side thereof and extending upwardly above the holder, said trips having 75 slots in which said rod has guided movement, and adjustable members on the said rod adapted to be engaged by the said trips.

5. A structure of the character described having a compartment, a slidable holder therein, a door to close the compartment in 85 front of the holder, a rod ranging longitudinally of the compartment adjacent to the holder and having an articulated connection with the door, said holder and rod having co-acting members to actuate the one by a 90 movement of the other.

6. A structure of the character described having a compartment, a slidable holder tray therein, a swinging door hinged at its upper end and extending at its lower end in 95 front of the tray, a resilient catch on the tray having a handle extending through the door to the outside, means on the structure to engage said catch, and means to actuate the door by movement of the tray.

7. A structure of the character described having a compartment, a sliding tray therein having transverse rests formed with V-shaped notches adapted to receive music rolls, and a transverse stop member rearward of said rests to limit the inward position of the rolls.

8. A structure of the character described having a compartment and a sliding tray 100 therein having rests adapted to receive music rolls, the said tray having its front depressed below the upper edge of the said rests.

In testimony whereof I have signed my name to this specification in the presence of 115 two subscribing witnesses.
